UNITED STATES PATENT OFFICE.

BENJAMIN H. PAXTON, OF GASSAWAY, WEST VIRGINIA.

CAR REPLACER.

Application filed June 8, 1927. Serial No. 197,424.

This invention relates to devices used for directing the wheels of de-railed cars, locomotives, etc., to the track and has for its object to provide such a device which is 5 strong and durable in operation and which is so designed as to permit its use on varying track structures, around switches, guard rails, etc.

Another object of the invention resides 10 in the provision of novel means for immovably anchoring the retracker in place adjacent the rails in such manner that the anchoring means itself is concealed and therefore protected from damage or destruction 15 by the wheels that are to be replaced on the rails.

A further object of the invention consists in providing an anchoring means for the replacer which is readily adjustable so 20 as to vary the position of the replacer with respect to the rail in cases where the car wheel to be replaced is some distance from the rail.

Other objects and advantages of the in- 25 vention will be apparent from the following description when taken in connection with the accompanying drawing; in which

Figure 1 is a perspective view of the car replacer in operative position against the 30 rail.

Figure 2 is an end view of the device partly broken away and showing in side elevation the clamping means.

Figure 3 is a bottom plan view of the 35 replacer; and

Figure 4 is a perspective view of the clamp and locking pin.

Referring to the drawing in greater detail, the numeral 1 indicates the car replacer 40 which is provided with a rounded or beveled top portion 2, a flat bottom portion 3, and side walls 4 and 5, which is adapted to be held in clamped position against the head of the rail as shown in Figure 2, or 45 which may be spaced therefrom in a manner to be later described.

The clamping or coupling members are indicated by the numeral 6 and are provided at one end with the hook 7 which engages 50 over the base of the rail as clearly shown in Figure 2. These coupling members are each provided on their ends opposite the hook 7 with an upright finger 8 provided

with apertures 9 adapted to receive a locking pin 10.

To prevent relative movement of the replacer with respect to the crossties of the rail bed the bottom portion 3 of the replacer is provided with spurs 11 which are adapted to dig into the upper surface of the ties 60 and prevent longitudinal or transverse movement of the replacer. The bottom of the car replacer is also provided with a plurality of apertures 12 adjacent each end thereof but spaced inwardly from the spurs 65 11. These apertures are adapted to receive the upright finger 8 for securing the car replacer in position against the rail, and it should be particularly noted that these two sets of apertures 12 are spaced apart a distance equal to the standard distance between 70 adjacent ties in a rail bed.

The purpose of this exact relationship between the two sets of apertures is to lock 75 the coupling members or clamps 6 adjacent the sides of the ties as shown in the bottom plan view in Figure 3. Obviously, when the clamps are so locked they will aid in preventing movement of the replacer longitudinally of the rail when the car wheel 80 comes into contact with the replacer.

The plurality of apertures 12 have a distinct function in that they not only adapt 85 the replacer to be used with rails of different sizes, but they also serve to permit the replacer to be placed at different positions with respect to the rail. For instance, if the car wheels are a considerable lateral distance from the rail the fingers 8 may be placed in an aperture which will permit 90 the replacer to be spaced a substantial distance from the rail so as to guide the wheel over toward the rail, and to be eventually guided up onto the head of the rail.

In clamping the car replacer in position 95 with respect to the rail the hooks 7 are engaged over the base of the rail and the finger 8 then inserted through the selected one of the apertures 12, after which the locking pin 10 is inserted through the aperture 9 in the upper end of the finger. For 100 the purpose of performing this latter operation, the wall 4 of the replacer is provided with the cut-out portions 13 and in order that the replacer may fit snugly up against 105 the rail the front edge of the bottom por-

tion is provided with cut-out portions or depressions 14 to receive the heads of the spikes which anchor this portion of the rail to the ties.

6 From the foregoing description taken in connection with the accompanying drawings it will be apparent that I have devised a relatively simple and inexpensive form of car replacer and coupling means therefor, by 10 which the replacer may be variously positioned with respect to the rail depending upon the particular location of the wheel to be replaced; that the coupling means are so positioned as to cooperate with the crossties in preventing longitudinal movement of the replacer; that the coupling means is so designed and constructed as to be entirely below the car replacer and the rail so as to prevent injury thereto by the car wheel; and 20 that the coupling, as herein designed, permits the use of this replacer on parts of a track heretofore found practically impossible, namely, around switches, guard rails, and the like.

25 In accordance with the patent statutes I have described what I now believe to be the best embodiment of the invention, but I do not wish to be understood thereby as limiting myself or the scope of the invention, as 30 many changes and modifications may be made without departing from the spirit of the invention; all such I aim to include within the scope of the appended claims.

What I claim as new and desire to secure 35 by Letters Patent is:

1. A car replacer including a body portion

having a rounded top and a flat bottom provided with a plurality of apertures adjacent one end thereof, a coupling member having a rail engaging end, and a finger on the 40 opposite end of the coupling adapted to be received in a selected one of said plurality of apertures.

2. A car replacer including a body portion having a rounded top and a flat bottom provided with a plurality of apertures adjacent each end thereof, a coupling member for each end of the replacer, each including a rail-engaging end and a finger at its opposite end to be received in a selected one of said 45 plurality of apertures.

3. A car replacer including a body portion having a beveled top and a flat bottom provided with a plurality of apertures adjacent each end thereof, the two sets of apertures being spaced apart a distance substantially equal to the distance between adjacent crossties, coupling members having rail engaging ends, and fingers on the opposite ends of said 50 members to be received in selected apertures in the bottom of the replacer.

4. A car replacer including a body portion having a beveled top and a flat bottom provided with a plurality of apertures adjacent each end thereof, a plurality of spurs formed on the bottom at each end thereof, coupling members, a hook on one end of each coupling member for engaging the base of a rail, an upright finger on the opposite end of each coupling member adapted to be locked in one 55 of said apertures.

BENJAMIN H. PAXTON.
